TOY

Louis Marx, New York, N. Y.

Application June 29, 1935, Serial No. 28,989

30 Claims. (Cl. 46—213)

This invention relates to toys, and more particularly to mobile or traveling toys.

The primary object of the present invention is to generally improve mobile or traveling toys in order to make the same universally operable under almost all circumstances and conditions. The toy may take any of a variety of external forms simulating an automobile, a motorcycle, a tractor, a rabbit, a mouse, a cat and so forth.

10 A more particularized object of the invention is to make the toy operable even when running toward a wall or similar obstruction, the toy simply turning aside and continuing its travel. The toy may also be arranged to turn safely aside on approaching an unobstructed table edge or like precipice, and it is a further object of the present invention to advantageously combine both of the aforesaid safety features or mechanisms in a simplified and economical mechanism. Still 15 another object of the invention is to improve the operation of the toy by minimizing friction at the front end of the toy whether propelled in a forward direction or swerved sidewardly.

The toy as so far described operates in a 20 mystifying and highly amusing manner, but these characteristics are enhanced in accordance with a further feature and object of my invention, whereby the toy is made to automatically follow closely around a peripheral wall such as the side wall of a block which may have a rectangular, circular or other configuration. The mechanism producing this effect may also be used to cause the toy to revolve immediately around an upright match, pencil or like obstruction.

25 To best demonstrate with convenience the many puzzling and amusing features of my invention, I have devised a special base or plate to be used in combination with the toy. This base is preferably made hollow and is bordered by a peripheral flange of suitable height to act as a wall so that the toy may be run around the base to demonstrate its tendency to hug the wall of the base, on top of the base to illustrate the safety feature whereby it swerves and remains on the 30 plate when it reaches the edge of the plate, and to show the collision feature by simply inverting the base and running the toy inside the base. Further objects of my invention are to equip the base with an optionally usable opening or trap in which the toy may be made to revolve, and to 35 further provide the base with a small socket dimensioned and adapted to receive a match or like obstruction about which the toy readily and rapidly revolves.

40 55 To the accomplishment of the foregoing and

other objects which will hereinafter appear, my invention consists in the toy elements and their relation one to the other as are hereinafter more particularly described in the specification and sought to be defined in the claims. The specification is accompanied by drawings in which:

Fig. 1 is a perspective view showing a vehicle toy operating on and combined with a suitable base;

Fig. 2 is a section taken in elevation through the 10 toy;

Fig. 3 is a section taken in plan on the line 3—3 of Fig. 2;

Fig. 4 is an inverted plan view showing the 15 front end of the toy;

Fig. 5 is a plan view illustrating the toy operating in combination with the base in inverted condition;

Fig. 6 is a plan view showing the toy operating around the periphery of the base;

Fig. 7 illustrates the toy revolving about a 20 match or like obstruction;

Fig. 8 is a detail explanatory of the match support and a trap for the toy;

Fig. 9 is a partially sectioned elevation ex- 25 planatory of the operation of the trap; and

Fig. 10 is a plan view showing the toy revolving in the trap.

Referring to the drawings, the mobile or traveling toy is here illustrated in the form of an automobile. The toy comprises a toy body T within which is housed a suitable driving motor or spring motor M best shown in Figs. 2 and 3. The motor rotates one of the running wheels, in the present case the left rear wheel or driving 30 wheel D. The toy is further equipped with two different types of turning wheels, one being the cross wheel C rotatable on an axis extending transversely of the running wheel axis, and the other being the bumper wheel B rotatable on an axis transverse of the axes of both the running 35 and cross wheels. The cross wheel C and bumper wheel B are preferably though not necessarily power driven by appropriate gear connections to the spring motor M. Bumper wheel B is concealed within the toy body except for its forward periphery which is exposed and acts as a bumper. When the toy reaches a wall, the rotation of bumper wheel B causes the toy to swing aside and to continue its travel in a new 40 direction, as is indicated in Fig. 5 of the drawings. To facilitate swerving of the toy, the forward end preferably rests upon a feeler F preferably 45 consisting of an anti-friction ball bearing as is best shown in Figs. 2 and 4 of the drawings. 50 55

The cross wheel C is elevated slightly above ground level when the toy rests on feeler F, this being evident in Fig. 2. However, when the toy reaches an edge or precipice, cross wheel C is lowered into engagement with the ground or running surface and is thereupon made effective to swing the toy around to a new and safe direction, as is best shown in Fig. 1 of the drawings.

The side of the toy opposite driving wheel D is preferably provided with a suitable projection A conveniently formed by extending the rear axle. The retarding influence of projection A combined with the off-center propulsion force caused by driving wheel D results in the toy hugging the peripheral wall of any suitable object such as the base P, so that the toy moves along and turns sharp corners about the base, as is best shown in Fig. 6. The shape and action of feeler F facilitates this, as well as the other turning movements of the toy.

Considering the arrangement in greater detail, the toy body T is preferably stamped from sheet metal and comprises a single shell 12 which simulates the top and sides of the hood and body of the automobile. For economy, front wheels are eliminated but are simulated by suitably shaping and indenting the sides of the body, as is indicated at 14 in Figs. 1 to 3. To conceal the mechanism and to greatly strengthen the toy structure, the open side of shell 12 is closed by a bottom plate 16 which extends all the way from the front to the back of the toy. This plate is preferably horizontal and comprises a central lowermost portion 18 which is stepped upwardly at 20 and then bent sidewardly or horizontally at 22 to meet the side edges of shell 12. This construction gives the bottom 16 a channel formation which stiffens and rigidifies the bottom and thereby strengthens the entire toy body. The shell 12 and bottom 16 are connected by inwardly bent interlocking flanges 19 and 21 and tongue and slot connections 23. The bottom is, of course, cut away to clear the running wheels and the cross wheel C.

The body is completed by a radiator simulation 24 provided at its sides with simulated headlights 26 (see Fig. 5) and flaring upwardly and outwardly at the bottom to form an apron 28 which overlies and conceals all of bumper wheel B except its outermost periphery. The structural appearance resembles an automobile bumper.

The motor M may be generally conventional and as here illustrated comprises a motor frame 30 carrying a squared stem or shaft 32 on which is wound a suitable spring 34. The shell 12 is cut away at 36 opposite one end of stem 32, thereby affording access to the winding stem which may be wound by inserting a conventional key.

The stem 32 carries a main driving gear 38 which may be fitted in the conventional manner with suitable ratchet mechanism 40 to facilitate winding the main spring. Gear 38 meshes with pinion 42 fixed to a gear 44 which in turn meshes with a pinion 46 mounted on the rear axle 48 of the vehicle. The operating speed of the motor may if desired be limited by suitable governor mechanism here comprising a step-up gear train including gear 58, pinion 52, gear 54 and pinion 56. The latter carries an eccentric or unbalanced weight 58.

Driving wheel D is forced directly on the splined end 60 of axle 48 and is directly driven thereby. The wheel D may be made of any suitable material, but I prefer to stamp the same directly from heavy gauge sheet metal. The edge of the re-

sulting disc or wheel is preferably milled or roughened as indicated at 62. This type of wheel provides adequate traction for propulsion of the toy, yet may slip slightly when the vehicle is positively obstructed. This is of assistance during the operation of the bumper wheel B, for the radius about which the toy is turned may theoretically cause a difference in speed between the bumper wheel and the driving wheel, which would interfere with proper operation of the toy if both wheels were perfectly frictional or incapable of slippage. This feature is also of assistance during the operation of the cross wheel C, for when the toy reaches a precipice, as when running over the edge of a glass or other smooth table top, the slight slippage permitted the driving wheel D when the cross wheel C first strikes the table works in the direction of safety, for the cross wheel C is given an opportunity to come into effective operation, without the continued propulsive effort of driving wheel D meanwhile or too soon forcing the toy over the precipice.

The other running wheel 64 may be made of oppositely convexed discs of sheet metal. This wheel is slipped over axle 48 and is held in place by pinching the axle at 66. The wheel is preferably an idle wheel freely rotatable on the axle.

The bumper wheel B is preferably provided with a rubber periphery or tread. This is most simply done by forming the wheel of a disc of 30 rubber 70 supported between metallic discs 72. The assembled wheel is rotatably mounted on an upright shaft or spindle 74 supported in suitable bearings 76 and 78 secured to the bottom plate 16 of the toy. The bumper wheel is operative even if left idle because of the biased or unsymmetrical turning effort caused by the use of only a single driving wheel. However, I prefer to make the toy positive and rapid in operation by positively driving the bumper wheel, and to this end the 40 wheel is secured to a crown gear 80 meshing with a pinion 82 mounted on a propeller shaft 84 extending longitudinally of the toy and carrying at its rear end a pinion 86 which meshes with a crown gear 88 fixed on axle 48. Because of its 45 length, and because of the necessity for locating the cross wheel C with extreme accuracy, the propeller shaft 84 is carried in bearings not only at the ends 90 and 92 but also at an intermediate point 94 immediately adjacent the cross wheel C 50 where the propeller shaft passes through the motor frame 30.

The cross wheel C is preferably provided with a rubber rim or periphery and this is most simply done by forming the wheel of a rubber disc 96 supported between metallic discs 98, the assembly being secured to and rotated by propeller shaft 84. The diameter of the cross wheel is of course so selected that the wheel normally clears the surface on which the toy is run.

It should be noted that the direction of rotation of the turning wheels is such that the useful portion of the bumper wheel periphery moves toward that side of the toy having the drive wheel D. Specifically, where the drive wheel is the left wheel, as in the present case, the forward periphery of bumper wheel B moves toward the left, as is indicated by the arrow in Fig. 5 of the drawings. Likewise the bottom of cross wheel C moves toward the left. In each instance the turning 70 wheel tends to swerve the vehicle toward the right and this change in direction is facilitated by the drive wheel at the left side of the vehicle.

The forward end of the toy rests on and is carried by the feeler F here exemplified by a ball 75

bearing 100 carried in a socket 102 located above a suitable opening in the bottom 16 of the toy and secured in place by outwardly bent tongues 104. As is best shown in Fig. 4, the perforation 5 in bottom 16 is smaller in diameter than the ball bearing and is outwardly recessed at diametrically opposite points to receive the depending tongues 104 of the socket or housing 102. The socket and toy bottom cooperate to encompass 10 somewhat more than a hemisphere of the ball bearing 100, thereby retaining the same in place. The less than hemispherical, downwardly projecting portion of the ball bearing runs on the table surface and is particularly desirable in this connection because so much of the movement at the 15 front end of the toy is sideward as well as forward. The ball bearing is of course universally movable. When it rolls over the edge of the base or table it is readily rolled sidewardly back onto 20 the table by the cross wheel. The pressure and consequently the friction at the front end of the toy may of course be reduced by weighting the back end of the toy, as indicated by the weight 106 immediately surrounding the motor frame 30, 25 as is best shown in Figs. 2 and 3 of the drawings. This weight compensates for the bumper wheel and related mechanism at the front end of the toy.

The operating possibilities with this toy are not only amusing but mystifying and are so numerous that I have found it extremely desirable and convenient to combine the toy with a special base designed to help demonstrate its capabilities. To this end I have devised the base P which is preferably formed of a generally rectangular piece of sheet metal which is pressed or drawn to form a flat operating surface or top 110 and a continuous peripheral flange 112. The edge 114 of the flange may be curved or beaded to prevent 30 injury and to give the same a finished appearance. The flange 112 is made greater in width than the elevation of the projection A and the bumper wheel B. The toy may be run on the top of the base as illustrated in Fig. 1, thus demonstrating the safety feature whereby it is safely 35 turned away when it reaches the edge of the plate. The toy may then be run around the edge of the base as illustrated in Fig. 6 in which case it hugs the edge of the base and turns at the corners 40 despite the fact that the corners are somewhat rounded as shown at 116. In fact, the toy will run around a circular block or plate. The base may then be inverted and the toy placed inside the flange or wall, as is best shown in Fig. 5. In 45 this case the toy runs toward the wall and on striking the same is turned aside until it reaches the next wall, and so on.

If desired, the base may be improved by forming a small socket at any point thereon sufficiently removed from the edge, this socket being dimensioned to receive one end of a match stick or the like. Thus in Figs. 7 and 8 the match stick 120 has been inserted in a socket 122. The toy runs back and forth over the top of the plate 50 in an erratic course until the right side of the toy happens to come close to or bear against the match or like obstruction. The axle projection A thereupon catches on the projection and the toy revolves around the obstruction as a center. 55 The socket 122 is here shown in the form of an eyelet for reasons next described, but it will be understood that it may consist simply of a small perforation in the sheet metal base.

If a hole of large diameter (but preferably 75 smaller than the diameter of wheel 64) is cut

through the plate as indicated at 124 in the drawings, this hole acts as a trap when the idle wheel 64 of the toy is placed or rolls into the same. The reason for this will be clear from examination of Fig. 9 in which it will be seen that when wheel 64 settles in hole 124 the cross wheel C is lowered into engagement with the base or plate. The vehicle then has two powered or driven wheels C and D which rotate at right angles to one another and which cause the toy to revolve 10 around the trap 124 as a center.

In order to make the trap optionally usable, I provide a cover 126 pivoted beneath the top of the base by an eyelet 122, this cover being movable from a position closing the trap as shown in 15 Figs. 7 and 8 to a position clearing or opening the trap as shown in Fig. 10. The center part of the cover 126 is preferably convexed or struck upwardly to fit into the opening 124 as is best shown in Fig. 8, so that when the trap is closed 20 the operating plate or base is characterized by a smooth level top surface. By pivoting the closure 126 on an eyelet, the eyelet may itself be used as a socket for a match as shown in Fig. 8.

It should be understood that various features 25 of the toy may be used independently of other features and it is not essential to combine all of the features in one toy as here illustrated, although such a toy possesses marked advantages. The projection A at the side of the toy need not 30 necessarily be formed by extending the axle as is here the case. The side projection feature may be used independently of the collision or bumper feature and the latter may be used independently of the cross wheel or safety feature, 35 whereby the toy turns away from an edge or precipice. While these features are independently usable, they are advantageously combined not only because the mechanism for driving the 40 cross wheel may also be used for driving the bumper wheel, but also because the feeler which is needed for cooperation with the cross wheel facilitates that sideward movement which is necessary for cooperation with the bumper wheel or collision feature as well as the side projection 45 feature. Furthermore, the provision of one fast and one loose rear wheel is highly important in connection with the side projection feature, and this is at the same time helpful though not absolutely essential in combination with the collision 50 and safety features. Of course, when the cross wheel and bumper wheel are powered, it is essential that they be rotated in the proper direction relative to the location of the side projection and the driving wheel.

The same chassis or mechanical arrangement 55 may be used with a variety of forms of toy and the performance of the toy is particularly effective when simulating an animal, for example, because the toy appears to possess an innate intelligence of its own as it follows its seemingly erratic but always safe course on or about the base, or circling when caught in the trap.

It is believed that the construction and operation as well as the many advantages of my improved toy will be apparent from the foregoing detailed description thereof. It will also be apparent that while I have shown and described my invention in preferred form, many changes and modifications may be made in the structure 70 disclosed without departing from the spirit of the invention defined in the following claims.

I claim:

1. A mobile toy, motor means therein to propel the toy, a normally ineffective turning wheel ar- 75

- ranged to cause the toy to swerve sharply to one side, said wheel being effective when the toy strikes a wall or like obstruction, whereby the toy continues its travel in a new direction.
5. 2. A vehicle toy comprising a body simulating an automobile, the forward end of said body being convex when viewed in plan, and a bumper wheel positioned generally horizontally on a generally upright spindle at the front end of the toy, said 10 wheel being concealed by the convex forward end of the toy, except for the forward part of the periphery of the wheel, the arrangement being such that when the wheel strikes a wall or obstruction the toy is turned aside.
15. 3. A toy comprising a body, a motor housed therein, a pair of wheels at the sides of the body, one of said wheels being loose and the other being positively driven by the aforesaid motor, a turning wheel arranged for rotation on a shaft transverse to the shaft of the side wheels, and means 20 connecting said turning wheel to the motor and rotating said wheel in a direction such that the useful part of its periphery moves toward that side of the toy having the driven wheel, and means 25 whereby the turning wheel is normally ineffective but becomes effective when the toy strikes a wall or similar obstruction.
4. A toy comprising a body, a motor housed therein, side wheels at least one of which is driven 30 by the aforesaid motor, a bumper wheel positioned generally horizontally at the front end of the toy, and means connecting said bumper wheel to the motor for rotating said bumper wheel.
35. 5. A toy comprising a body, a spring motor housed therein, a pair of wheels at the sides of the body, one of said wheels being loose and the other being positively driven by the aforesaid spring motor, a bumper wheel which is relatively large in diameter and positioned generally horizontally 40 for rotation on a generally upright shaft at the forward end of the toy, the forward part only of the periphery of said bumper wheel being exposed at the front end of the toy, and means connecting said bumper wheel to the spring motor for rotating said bumper wheel in a direction such that the exposed forward periphery moves toward that 45 side of the toy having the driven wheel, the arrangement being such that when the bumper wheel strikes a wall or obstruction the toy is turned aside and continues its travel.
50. 6. A vehicle toy comprising a vehicle body, a spring motor housed therein, a pair of rear wheels at the sides of the body, one of said wheels being loose and the other being positively driven by the aforesaid spring motor, simulated front wheels, and a bumper wheel which is relatively large in diameter and positioned generally horizontally for 55 rotation on a generally upright shaft, the forward part only of the periphery of said bumper wheel being exposed at the front end of the toy and being arranged to simulate a vehicle bumper.
60. 7. A toy comprising a body housing a motor, running wheels at the sides of said body, a first turning wheel rotatable on an axis transverse to that of the running wheels, a second turning wheel rotatable on an axis transverse to that of the running wheels and the first turning wheel, and gearing connecting the motor with a running wheel and the first and second turning wheels.
70. 8. A toy comprising a body housing a motor, wheels at the sides of said body, one of which is loose and the other of which is driven by said motor, a feeler at the forward end of the body on which the toy rests, a cross wheel between the rear wheels and the feeler, said cross wheel being

normally elevated slightly above ground level by the feeler, and a bumper wheel at the forward end of the vehicle for rotation about an upright axis and having its forward periphery exposed beyond the end of the vehicle.

9. A toy comprising a body housing a motor, wheels at the sides of said body at least one of which is driven by said motor, a feeler at the forward end of the body on which the toy rests, a cross wheel between the rear wheels and the feeler, 10 said cross wheel being normally elevated slightly above ground level by the feeler, a bumper wheel at the forward end of the vehicle for rotation about an upright axis and having its forward periphery exposed beyond the end of the vehicle, 15 and gearing connecting the motor with the cross wheel and bumper wheel for positively rotating the same.

10. A toy comprising a body housing a spring motor, wheels at the sides of said body, one of 20 which is loose and the other of which is driven by said spring motor, a feeler at the forward end of the body on which the toy rests, a cross wheel between the rear wheels and the feeler, said cross wheel being normally elevated slightly above 25 ground level by the feeler, a bumper wheel at the forward end of the vehicle arranged for rotation about an upright axis and having its forward periphery exposed beyond the end of the vehicle, and gearing connecting the spring motor with 30 the cross wheel and bumper wheel for positively rotating the same, the gearing being arranged to rotate the said wheels in such direction that the bottom periphery of the cross wheel and the forward periphery of the bumper wheel move toward 35 the side of the vehicle having the driven side wheel.

11. A toy comprising a body carrying a motor, wheels at the sides of said body, one of which is loose and the other of which is positively driven 40 by the spring motor, a feeler at the forward end of the body, said feeler consisting of a ball bearing mounted on the body and projecting downwardly therefrom, and a turning wheel for changing the direction of travel of the toy.

12. A toy comprising a body carrying a motor, a running wheel driven by the motor, a feeler at the forward end of the body, said feeler consisting of a ball bearing mounted on the body and projecting downwardly therefrom, and a turning 50 wheel also driven by the motor.

13. A toy comprising a body carrying a motor, wheels at the sides of said body, one of which is loose and the other of which is positively driven by the motor, a feeler at the forward end of the 55 body, said feeler consisting of a ball bearing mounted on the body and projecting downwardly therefrom, a cross wheel located between the rear wheels and the feeler, said cross wheel being normally elevated slightly above ground level by the 60 feeler.

14. A toy comprising a body carrying a spring motor, wheels at the sides of said body, one of which is loose and the other of which is positively driven by the spring motor, a feeler at the forward end of the body, said feeler consisting of a ball bearing mounted on the body and projecting downwardly therefrom, a cross wheel located between the rear wheels and the feeler, said cross wheel being normally elevated slightly above 70 ground level by the feeler and being positively driven by the spring motor in a direction such that the bottom periphery of the wheel moves toward that side of the toy having the driven rear wheel.

15. A toy comprising a body housing a motor, wheels at the sides of said body, one of which is idle and the other of which is positively driven by the motor, and a projection at that side of the body having the idle wheel, the arrangement being such that the toy if placed alongside an obstruction or block with the driven wheel on the outside, tends to turn about the obstruction or block because of the retarding influence of the aforesaid projection.

16. A toy comprising a body housing a spring motor, wheels at the sides of said body, one of which is idle and the other of which is positively driven by the spring motor, the axle of said wheels being projected sidewardly beyond the body of the toy to form a projection at that side of the body having the idle wheel, the arrangement being such that the toy if placed alongside an obstruction or block with the driven wheel on the outside, tends to turn about the obstruction or block because of the retarding influence of the aforesaid projection.

17. A vehicle toy comprising a vehicle body housing a motor, simulated front and rear wheels at the sides of said body, one of said rear wheels being idle and the other being positively driven by the motor, the rear axle of said toy being projected sidewardly beyond the body of the toy to form a projection at that side of the body having the idle rear wheel, the arrangement being such that the toy if placed alongside an obstruction or block with the driven wheel on the outside, tends to turn about the obstruction or block because of the retarding influence of the aforesaid projection.

18. A toy comprising a body housing a motor, a pair of wheels at the sides of said body, one of which is idle and the other of which is driven by said motor, a feeler at the forward end of said body shaped to facilitate sideward movement, a cross wheel intermediate the feeler and wheels, and a projection extending sidewardly on that side of the body having the idle wheel.

19. A toy comprising a body housing a motor, a pair of wheels at the sides of said body, one of which is idle and the other of which is driven by said motor, a feeler at the forward end of said body, and a cross wheel intermediate the feeler and wheels, said cross wheel being normally elevated above the ground level by said feeler, the wheel axle being extended on that side of the body having the idle wheel in order to form a projection beyond the body of the toy.

20. A toy comprising a body housing a spring motor, a pair of rear wheels at the sides of said body, one of which is idle and the other of which is driven by said spring motor, a feeler at the forward end of said body in the form of a ball bearing, a cross wheel intermediate the feeler and rear wheels, said cross wheel being normally elevated above the ground level by said feeler and being driven by said spring motor, with the bottom periphery moved toward that side of the toy having the driven rear wheel, the rear wheel axle being extended on that side of the body having the idle wheel in order to form a projection beyond the body of the toy.

21. A toy comprising a body, running wheels at the sides thereof, a feeler at the front end thereof, a cross wheel between the feeler and the running wheels, said cross wheel being normally elevated from the ground by the feeler, a bumper wheel projecting at the front end of the toy and rotatable on an upright axis, a sideward projection at one side of the toy, and a motor in said

toy driving that running wheel at the side of the toy opposite the projection, and thereby tending to turn the toy whether in cooperation with either the cross wheel or the bumper wheel or the sideward projection.

22. In combination, a toy comprising a body housing a motor, a pair of wheels at the sides of said body, one of which is idle and the other of which is driven by said motor, the wheel axle being extended on that side of the body having the idle wheel in order to form a projection beyond the body of the toy, and a base comprising a flat running surface and a peripheral side wall, said side wall being greater in height than the elevation of the aforesaid axle projection, whereby the toy may be run around the base.

23. In combination, a toy comprising a body housing a motor, a pair of wheels at the sides of said body, one of which is idle and the other of which is driven by said motor, a feeler at the forward end of said body, a cross wheel intermediate the feeler and wheels, said cross wheel being normally elevated above the ground level by said feeler, a sideward projection on that side of the body having the idle wheel, and a base comprising a flat running surface and a peripheral side wall, said side wall being greater in height than the elevation of the aforesaid projection, whereby the toy may be run on top of the base and may also be run around the base.

24. In combination, a toy comprising a body housing a motor, a pair of wheels at the sides of said body, one of which is idle and the other of which is driven by said spring motor, a feeler at the forward end of said body, a cross wheel intermediate the feeler and wheels, said cross wheel being normally elevated above the ground level by said feeler and being driven by said motor, a sideward projection on that side of the body having the idle wheel, and a base comprising a piece of sheet metal pressed or drawn to form a flat running surface and side flanges, the top surface of said base having a hole dimensioned to receive the end of a match or other pin pushed therein, whereby the toy may be run in a circular path about the upwardly projecting pin, or in an erratic course over the top of the base.

25. In combination, a toy comprising a body housing a motor, a pair of wheels at the sides of said body, one of which is idle and the other of which is driven by said motor, a feeler at the forward end of said body, a cross wheel intermediate the feeler and wheels, said cross wheel being normally elevated above the ground level by said feeler and being driven by said motor, and a base comprising a piece of sheet metal pressed or drawn to form a flat running surface and side flanges, the top surface of said base having a relatively large hole or trap cut there-through, a cover plate movably mounted to cover or uncover said hole or trap, whereby the toy may be run in a circular path about the hole or trap, or in an erratic course over the top of the base.

26. In combination, a toy comprising a body housing a motor, wheels at the sides of said body, one of which is loose and the other of which is driven by said motor, and a bumper wheel located at the forward end of the vehicle for rotation about an upright axis and having its forward periphery exposed beyond the end of the vehicle, and a base, said base comprising a flat bottom with a continuous peripheral flange, said flange being greater in width than the elevation

of the bumper wheel, whereby the toy may be operated inside the base.

27. In combination, a toy comprising a body housing a motor, wheels at the sides of said body, one of which is loose and the other of which is driven by said motor, a bumper wheel located at the forward end of the vehicle for rotation about an upright axis and having its forward periphery exposed beyond the end of the vehicle, gearing connecting the motor with the bumper wheel, and a sideward projection at the side of the body having the idle rear wheel, and a base, said base comprising a piece of sheet metal pressed or drawn to form a flat surface with a continuous peripheral flange, said flange being greater in width than the elevation of the projection and the bumper wheel, whereby the toy may be operated around the outside of the base or inside the base.
28. In combination, a toy comprising a body housing a motor, wheels at the sides of said body, one of which is loose and the other of which is driven by said motor, a feeler at the forward end of the body on which the toy rests, a cross wheel between the wheels and the feeler, said cross wheel being normally elevated slightly above ground level by the feeler, a bumper wheel located at the forward end of the vehicle for rotation about an upright axis and having its forward periphery exposed beyond the end of the vehicle, and a base, said base comprising a flat surface with a continuous peripheral flange, said flange being greater in width than the elevation of the bumper wheel, whereby the toy may be operated on top of the base or inside the base when the base is inverted.
29. In combination, a toy comprising a body housing a motor, wheels at the sides of said body, one of which is loose and the other of which is driven by said motor, a feeler at the forward end of the body on which the toy rests, a cross wheel

between the wheels and the feeler, said cross wheel being normally elevated slightly above ground level by the feeler, a bumper wheel located at the forward end of the vehicle for rotation about an upright axis and having its forward periphery exposed beyond the end of the vehicle, a sideward projection at the side of the body having the idle rear wheel, and a base, said base comprising a flat surface with a continuous peripheral flange, said flange being greater in width than the elevation of the projection and the bumper wheel, whereby the toy may be operated on top of the base or around outside of the base or inside the base when the base is inverted.

30. In combination, a toy comprising a body housing a spring motor, wheels at the sides of said body, one of which is loose and the other of which is driven by said spring motor, a feeler at the forward end of the body on which the toy rests, a cross wheel between the rear wheels and the feeler, said cross wheel being normally elevated slightly above ground level by the feeler, a bumper wheel located at the forward end of the vehicle for rotation about an upright axis and having its forward periphery exposed beyond the end of the vehicle, and gearing connecting the spring motor with the cross wheel and bumper wheel for positively rotating the same, the rear axle of said toy being extended at the side having the idle rear wheel in order to form a projection beyond the side of the toy, and a base, said base comprising a generally rectangular piece of sheet metal pressed or drawn to form a flat surface with a continuous peripheral flange, said flange being greater in width than the elevation of the axle projection and the bumper wheel, whereby the toy may be operated on top of the base or around outside of the base or inside the base when the base is inverted.

LOUIS MARX.
